UNITED STATES PATENT OFFICE.

GEORGE SWITZER, OF LODI, OHIO.

CAR-COUPING.

SPECIFICATION forming part of Letters Patent No. 517,967, dated April 10, 1894.

Application filed July 3, 1893. Serial No. 479,480. (No model.)

To all whom it may concern:

Be it known that I, GEORGE SWITZER, a citizen of the United States, residing at Lodi, in the county of Medina and State of Ohio, have 5 invented certain new and useful Improvements in Car-Couplers; and I do declare the following to be a full, clear, and exact description of the invention, such as will enable others skilled in the art to which it appertains to 10 make and use the same, reference being had to the accompanying drawings, and to the letters of reference marked thereon, which form a part of this specification.

This invention relates to link-and-pin car 15 couplers, and the invention consists in certain improvements of construction hereinafter fully set forth whereby the proper automatic coupling of the cars is facilitated.

The improvements reside, first, in the means 20 for holding and adjusting the coupling-link to enable it to enter coupling-heads of varying heights, second, in the means for holding the coupling-pin in its elevated position before coupling and permitting it to drop to engage 25 the link when the drawheads come together, and third, in means for preventing the coupling-pin from being jolted out of engagement with the link.

The drawings illustrate the drawheads of 30 adjacent cars with the improvements applied thereto.

Figure 1, is a central longitudinal vertical section of the two adjacent coupling-heads with the coupling mechanism in position to 35 automatically couple the cars when the drawheads come together. Fig. 2, is a side elevation of the coupling-head supporting the link. Fig. 3, is a front view of the coupling head with the coupling-pin ready to engage with 40 the link. Fig. 4, is a horizontal section of the coupling-head in the plane indicated by the dotted line 4—4 in Fig. 2. Fig. 5, is a vertical transverse section on the line 5—5 in Fig. 4, showing a detail of construction.

45 Each drawhead A, is formed with a longitudinal cavity a c extending inward from the front face of the coupling-head, a vertical pin-hole b near the front of the coupling-head, and an oblique slot d below the longitudinal cavity. The forward flaring portion a of the longitudinal cavity constitutes the usual opening into which the coupling-link A enters to en-

gage with the coupling-pin, said opening being continued back into the draw-head to form the cylindrical bore c within which fits and 55 slides a cylindrical bar or bolt C for holding the coupling-pin in an elevated position preparatory to coupling the cars. The vertical hole b is the usual pin-hole intersecting the cavity a and accommodating the coupling-pin 60 B. The oblique slot d traverses the lower part of the coupling-head below the link cavity a and forms a guide for the sliding link-set D hereinafter more particularly described.

The bar or bolt C within the continuation 65 c of the link cavity a, is designed to be moved forward when it is desired to elevate one of the coupling-pins of approaching cars preparatory to coupling, the pin being first raised and the bolt C then advanced so that its front 70 end projects across the pin-hole b and supports the pin in its raised position. The bolt is of cylindrical form sliding freely within its cylindrical cavity c, this form of bar making the movement more smooth and easy.

An operating stud s is formed on the side 75 of the bolt C, and extends into a bayonet groove or slot t cut in the side of the coupling-head. The bolt is moved out manually (by manipulation of the stud s) to support 80 the coupling-pin, and then when the cars come together the bolt is automatically pushed back and is locked by the stud s entering the downwardly-projecting portion of the slot t (see Fig. 2). The stud s should project but 85 little (if any) outside of the slot so as not to protrude objectionably, and in order to give at the same time sufficient space for the fingers to manipulate the stud the lower margin of the longitudinal portion of the slot is bevelled or cut away obliquely as indicated in the drawings at t' (Figs. 2 and 5). If preferred, the manual operation of bolt C may be dispensed with and the bolt rendered completely automatic in its action by omitting the stud s 90 and slot t and putting a coiled spring behind the bolt, as has been heretofore done in this class of car-couplers, so that when the coupling-pin is raised the bolt will be automatically projected by the spring and the pin 95 held elevated until the bolt is pushed back by the link of the approaching car.

The link-set D consists of the stem D' which extends through the slot d, and the link-sup-

porting plate D carried at the upper forward end of said stem. The slot d extends obliquely through the lower portion of the coupling-head, being intersected by the pin-hole b, and the forward end of the slot d is just below the link cavity a. While the plate D of the link-set remains in its most inward position against the front of the coupling-head, it does not affect the position of the coupling-link; but when the link-set is moved forward, the plate D stands below and supports the projecting end of the coupling-link A, and the coupling-link can be set at any desired angle (according as may be required by the height of the coupling-head of the other car) by adjusting the position of the link-set. Guided by the stem D' and the slot d, the link-supporting plate D will be raised higher and higher the farther forward it is moved.

20 To prevent the link-set from being pulled entirely out of its slot d, the stem D' is longitudinally slotted as shown (Figs. 1, and 3), and the lower end of the coupling-pin B extending down through the pin-hole b stands within the slot of stem D', as shown at the left in Fig. 1, so that the link-set can be drawn forward only until the rear end of the slot of stem D' encounters the point of the coupling-pin B. Since the link-set is only drawn out when the coupling-head carries a link, the coupling-pin B of that coupling-head is never raised while the link-set is being manipulated, and so the coupling-pin is always in position to prevent the accidental removal of the link-set. But 30 when the coupling-head is not carrying a link and the coupling-pin is elevated, as at the right of Fig. 1, there is no occasion to manipulate the link-set of that coupling-head at all, and the link-set in that case is not retained 35 by the coupling-pin but is retained within its inclined slot d by gravity merely. In any case, if it is desired to remove the link-set it is only necessary to raise the point of the coupling-pin out of engagement with the slotted stem D'. The front of the coupling-head is recessed below the cavity a and around the forward end of slot d, as indicated at x, Figs. 1 and 4, so as to accommodate the link-supporting plate D when the link-set is pushed 40 in to its inward position. When the link-set is so pushed in, the plate D occupies the recess x and so does not project at all beyond the face of the coupling-head but is flush therewith forming practically a part of the front of the coupling-head. The top edge of plate D is concave and forms the lower margin of the orifice of link cavity a, as best shown in Fig. 3. This concavity of the upper supporting edge of the plate D not only 45 makes the plate conform to the contour of the coupling-head when the link-set is pushed in but also better adapts the plate to support the link when the link-set is in use.

50 The means provided for holding the coupling-pin after it has dropped into engagement with the link consists of a retaining projection formed on the top of the coupling head

with which the pin automatically engages when it falls and which prevents the pin from being accidentally jolted out but at the same time permits the ready disengagement of the pin when it is desired to raise the same to uncouple the cars.

The construction is as follows:—Upon the top of the coupling-head near the pin-hole b is formed an overhanging lug or catch-plate m, which is rigidly attached to the coupling-head and is preferably cast integral therewith. As illustrated, the lug m is located directly in front of the pin-hole and nearly overhangs the front margin of the hole. Opposite to the lug m and adjacent to the opposite margin of the hole b, is an incline o which slopes backward and upward from the pin-hole. The coupling-pin B is formed with an annular flange n near its upper end extending horizontally, and this flange, co-operating with the lug m and incline o, effects the automatic securing of the pin. When the pin falls, one edge of the flange n slides down the incline o and thus guides the opposite edge of the flange under the overhanging lug or catch-plate m. The pin-hole b is of such diameter as to give a slight lateral play to the coupling-pin, and this permits the flange n of the pin to be guided laterally into the recess beneath lug m. The lug m overhanging the flange n of the pin prevents the vertical displacement of the pin by any jolting or jarring of the cars, but when it is desired to lift the pin the lug m constitutes no obstruction because the pin need only be moved slightly toward the incline o thus freeing flange n from lug m and allowing the pin to be raised.

Before coupling, the two adjacent couplers are arranged as shown in Fig. 1, of the drawings, the link A of one coupler being held at the proper height by the link-set D, and the pin B, of the other coupler being held elevated by the pin-holding bolt C. When the two cars come together, the link A enters the link cavity a of the other coupler, pressing back the bolt C and letting the coupling-pin B drop into engagement with the link, and at the same time the link-set D which was supporting the link A is pushed in by the impact of the opposing coupling-head. The entire operation of coupling is thus automatic, and the coupling-pin also engages automatically with its retaining catch-plate m, as just described. To uncouple, the coupling-pin B is merely raised, and is held elevated if desired by the sliding bolt C.

In preparation for coupling, the co-operating link and pin of the approaching cars are set to their proper positions by the link-set D and pin-holding bolt C respectively, as hereinbefore fully described.

I claim as my invention—

1. The coupling-head having the recess x below and adjacent to the orifice of the link cavity, in combination with the link-supporting plate D which in its inoperative position

occupies said recess and which has a concave upper edge constituting in its inoperative position the lower margin of said orifice, substantially as set forth.

- 5 2. In a car-coupler, the coupling-pin B and pin-hole *b*, in combination with the inclined slot *d* intersecting the lower portion of said pin-hole, and the link-set D having slotted stem D' adapted to slide in said inclined slot *d*, the slot of said stem D' registering with the pin-hole *b* and embracing the point of the coupling-pin, substantially as set forth.
- 10 3. The sliding bolt C having operating stud *s*, in combination with the slot *t* which said stud enters having a beveled margin *t'*, substantially as set forth.
- 15 4. In a car-coupler, the coupling-head O having pin-hole *b*, and the coupling-pin B, in

combination with a stationary lug *m* adjacent to the pin-hole *b* with which said coupling-pin automatically engages when dropped into the pin-hole, substantially as set forth.

5. In a car-coupler, the coupling-head O having pin-hole *b*, and the coupling-pin B having flange *n*, in combination with a stationary overhanging or laterally-recessed lug *m* on said coupling-head adjacent to said pin-hole, and a cam-incline *o* which guides the flange *n* of the coupling-pin into engagement with the lug *m*, substantially as set forth. 30

In testimony whereof I affix my signature in presence of two witnesses.

GEORGE SWITZER.
